DESIGN.

D. G. LITTLEFIELD.

MAGAZINE COAL STOVE.

No. 17,669.

Patented Aug. 30, 1887.

UNITED STATES PATENT OFFICE.

DENNIS G. LITTLEFIELD, OF ALBANY, NEW YORK.

DESIGN FOR A MAGAZINE COAL-STOVE.

SPECIFICATION forming part of Design No. 17,669, dated August 30, 1887.

Application filed August 31, 1883. Serial No. 105,247. Term of patent 14 years.

To all whom it may concern:

Be it known that I, DENNIS G. LITTLEFIELD, of the city and county of Albany, in the State of New York, have invented and produced a new and original Design for a Magazine Coal-Stove, of which the following is a specification, reference being had to the accompanying photographic illustration, which forms part thereof, and which is a perspective view of the front and one end of a stove embodying my design.

Heretofore magazine coal stoves having a magazine-section, two mica-light sections, and an ash-pit section have been made of a cylindrical or circular form, or approximating thereto.

The leading feature of my design consists of a form whose horizontal sections will consist substantially of an oblong rectangular figure, and whose vertical outlines are in the form shown in the accompanying illustration and described in this specification.

As represented in the accompanying illustration, A is a top ornament, which, as it may be replaced by an ornament of a different design, I do not desire to include in the design covered by this patent.

B is a top plate, composed of three upwardly-inclined angles and three horizontal planes arranged, as shown, in the form of unequal steps on the four sides of an oblong rectangle.

C is the magazine section, whose vertical outlines are composed of straight lines and whose horizontal outlines are in the form of an oblong rectangle with the corners slightly rounded. The said magazine-section includes the upper projecting frame, c, which consists of a deep beveled edge or curtain that is rounded on its upper part, to finish with a horizontal plane.

D is the upper mica-light section, having the form of a truncated oblong rectangular dome, and provided at its front and ends with doors d, containing mica lights. The said upper mica-section includes the projecting frame d', consisting of a beveled edge or curtain, rounded on its upper part to meet a horizontal plane, which joins to a quarter-round con-

50 vex molding.

E is the combined ash-pit and lower mica-light section, whose vertical outline is composed of the following parts: The lower portion, in its general outline, is composed of

straight lines until about one-half of the 55 height of the section is reached, when it curves inwardly for a short distance, and then terminates in an outwardly-flaring upper portion. The lower portion has in its front an ash-pit door, e, and at its ends the foot- rests e' project. The upper portion is provided on its front and ends with doors e'', designed for containing mica lights. The said lower section includes the projecting frame e'', whose form is like the frame d, hereinbefore described. 60

F is the stove bottom or base, which decreases in size as it rises, and whose lower member is a beveled band, which rounds over to join with a large convex quarter-round member that at its top abuts against a narrow vertical band which is succeeded by a wider flat level band. The latter is followed by a narrow vertical band at the base of a concave quarter-round, having at its top a flat horizontal band, which is succeeded by a 75 smaller convex quarter-round.

What I claim as my invention is—

1. In a design for a stove herein described and shown, the form, configuration, and ornamentation of the following parts: top plate, 80 B, magazine-section C, upper mica-light section, D, combined ash-pit and lower mica-light section, E, and base F, as herein specified.

2. In a design for a stove herein described and shown, the form, configuration, and ornamentation of the upper mica-light section, 85 D, consisting of a truncated oblong rectangular dome, as shown, provided at its ends and front with doors d, and a projecting frame, d', having a beveled curtain rounded at its 90 upper edge to meet a horizontal plane, the latter joining to a quarter round molding, as shown and described.

3. In a design for a stove herein described and shown, the form, configuration, and ornamentation of the combined ash-pit and lower mica-light section, E, consisting of a body whose vertical outlines are composed of vertical straight lines, inwardly-curved lines, and outwardly-flaring lines, arranged in the 100 order named, the said section being provided with the doors e and e'', as shown and described.

DENNIS G. LITTLEFIELD.
